UNITED STATES PATENT OFFICE.

MORITZ RHEINAUER, OF NEW YORK, N. Y.

DESIGN FOR A BOTTLE.

SPECIFICATION forming part of Design No. 34,062, dated February 12, 1901.

Application filed January 8, 1901. Serial No. 42,560. Term of patent 7 years.

To all whom it may concern:

Be it known that I, MORITZ RHEINAUER, a citizen of the United States, and a resident of the city of New York, borough of Manhattan, in the county and State of New York, have invented and produced a new and original Design for a Bottle, of which the following is a full, clear, and exact description.

Reference is to be had to the accompanying drawings, forming a part of this specification, in which similar characters of reference indicate corresponding parts in both the figures.

Figure 1 is a side elevation of a bottle, showing my design; and Fig. 2 is a section through the line 2 2 of Fig. 1.

The leading feature of my design for a bottle consists in an oval body with three cylindrical projections at one end, the said projections being exteriorly screw-threaded and the central projection having a greater length than those at the sides.

Referring particularly to the drawings, 5 designates the body portion of the bottle; which is oval in cross-section, 6 the center projection, and 7 the side projections, the 25 central projection having a greater length than the side projections. At the outer sides of the body longitudinal depressions 10 are shown.

Having thus described my invention, I 30 claim as new and desire to secure by Letters Patent—

The design for a bottle as herein shown and described.

In testimony whereof I have signed my 35 name to this specification in the presence of two subscribing witnesses.

MORITZ RHEINAUER.
